CLAIM

The ornamental design for a knife substantially, as shown and described.

DESCRIPTION

FIG. 1 is a perspective view of a folding knife, with the blade closed, showing my new design.

FIG. 2 is a perspective view thereof, showing the blade in an open position.

FIG. 3 is a rear elevational view thereof.

FIG. 4 is a front elevational view thereof.

FIG. 5 is a bottom plan view thereof.

FIG. 6 is a left side elevational view thereof.

FIG. 7 is a top plan view thereof; and,

FIG. 8 is a right side elevational view thereof.

Shading lines shown in the drawings are intended to represent the approximate three-dimensional contour of the design, and are not intended to indicate surface decoration. Features not shown in the drawings, or features depicted in broken lines, form no part of the claimed design.
